UNITED STATES PATENT OFFICE.

FRED B. SMALL AND JAMES C. MULLIGAN, OF BATH, MAINE.

WINDOW.

SPECIFICATION forming part of Letters Patent No. 651,210, dated June 5, 1900.

Application filed January 9, 1900. Serial No. 863. (No model.)

To all whom it may concern:

Be it known that we, FRED B. SMALL and JAMES C. MULLIGAN, citizens of the United States, residing at Bath, in the county of Sagadahoc and State of Maine, have invented 55 certain new and useful Improvements in Windows; and we do hereby declare the following to be a full, clear, and exact description of the invention, such as will enable others skilled 60 in the art to which it appertains to make and use the same.

This invention relates to improvements in windows; and the object thereof is to provide an improved construction whereby both of 15 the sashes may be quickly and readily reversed, so that the outer faces of the glass carried thereby may be conveniently cleaned from the inside of the room, thus obviating the danger and inconvenience incident to 20 cleaning the outer faces of the glass when the sashes are in their normal position.

The invention consists in the details of construction which are fully set forth in the following specification, particularly pointed out 25 in the annexed claims, and clearly illustrated by the accompanying drawings, in which—

Figure 1 is a perspective view illustrating our improved window, the parts being shown in position for the reversal of the sashes. Fig. 30 2 is a vertical sectional view showing the parts in their normal position, the sashes being shown in dotted lines. Fig. 3 is a similar view with swiveled plate in position for the reversal of the sashes.

Referring now more particularly to the accompanying drawings, A designates the window-frame, and B B two vertical strips carried by the inner faces of the side pieces of the frame and between which the sashes C 35 and D are positioned. Strips B B are recessed, as illustrated, said recesses extending from a point a short distance above the meeting ends of the sashes to a point in line with or slightly below said meeting ends of the 40 sashes. Secured in these recesses are the castings E E, formed at their lower ends with the raised circular portions F F, constituting pivots about which plates G G turn. These 45 swiveled plates are formed each with two parallel longitudinally-extending slots H and I, the slot H being longer than the slot I, so as to extend beyond the outer end of the latter.

The fixed pivots F F are each formed with the two parallel horizontally-extending slots J and K, the upper slot J extending to a point slightly beyond the center of the side rail of the upper sash and the lower slot K to the same point with respect to the lower sash. When these swiveled plates are swung 55 downwardly to horizontal position, the slots H and I, formed therein, register with and form continuations of the slots J and K of the pivots, and when said plates are swung upwardly to their normal positions the outer ends of slots J and K are closed by the walls 60 of the circular openings formed in the plates, as will be readily understood.

Each sash has the outer faces of its side rails grooved longitudinally, as at L, said grooves being dovetailed or formed with 70 flanges to retain the headed ends of pins or studs M, the opposite ends of the pins of the upper sash projecting into slots J of the fixed pivots F F, while the opposite ends of the pins of the lower sash project into slots K of 75 said pivots. The pins have their ends headed to prevent withdrawal from the slots of said pivots.

The upper sash at its lower end rests upon supporting-strips N, secured to the side strips 80 of the frame, while strips O and P, respectively, retain the upper and lower sashes in their normal positions. The upper walls of the castings are beveled, as illustrated, as are also the upper ends of the swinging plates, 85 and the latter carry the gravity-catches Q, having the handle portions Q'. The engaging ends of these catches engage the notches or openings R, formed in the upper walls of the castings. 90

The operation of our invention is as follows: As illustrated in Fig. 2 the sashes are in their normal positions. In this position the lower sash may be raised and lowered, it sliding on the studs or pins M, which are retained 95 in slots J and K of the pivots. To reverse the sashes, the catches are disengaged from the castings and the plates swung downwardly to horizontal position, as illustrated in Figs. 1 and 3, the slots formed therein registering 100 with the slots of pivots F F. The lower sash is then raised until its lower edge clears the retaining-strip P, when it may be drawn outwardly, its pins M moving in slots I of the

plates. The sash can then be raised until it can be readily reversed, turning on pins M as pivots. The upper sash is drawn outwardly, its pins M moving in slots H of the 5 plates, and reversed in the same manner. Thus the outer faces of the glass carried by said sashes may be readily cleaned from the inside of the room. The sashes may be quickly restored to their normal position and the 10 swiveled plates swung upwardly and locked by the gravity-catches, the operation being clear from the description and drawings.

Many slight changes might be made in the 15 details of construction without departing from the spirit and scope of our invention, and we do not, therefore, limit ourselves to the details of construction shown and described.

Having thus fully described our invention, 20 what we claim as new, and desire to secure by Letters Patent of the United States, is—

1. The combination with a window-frame, fixed pivots carried thereby and slotted horizontally, and plates adapted to swing on said 25 pivots and slotted, of a sash, and pins resting in the slots of said pivots and adapted to move in the slots of the plates and movably connecting said sash with said pivots and plates, substantially as described.

2. The combination with a window-frame, and downwardly-swinging plates carried thereby, of a sash, and means for connecting said sash to said plates whereby the sash is adapted to slide vertically when the plates are 35 raised, and is adapted to be drawn outwardly from the window-frame and reversed when said plates are swung downwardly, substantially as described.

3. The combination with a window-frame, 40 and downwardly-swinging slotted plates carried thereby, of a vertically-sliding sash, and pins upon which said sash slides, adapted to move in the slotted plates, whereby the sash may be drawn outwardly from the window-frame when the plates are swung downwardly, 45 substantially as described.

4. The combination with the window-frame, and slotted swiveled plates carried thereby,

of the sash having grooved side rails, and 50 studs engaging in the slots of the plates and grooves of the rails, substantially as described.

5. The combination with a window-frame, plates carried thereby and adapted to swing to horizontal position and formed with slots, catches for holding said plates raised, of the 55 sash having grooved side rails, and pins adapted to move in said slots and engaging in said grooves, substantially as described.

6. The combination with a window-frame carrying swinging slotted plates and pins 60 adapted to move in said slots, of a sash having a sliding connection with said pins, substantially as described.

7. The combination with the window-frame-carrying pivot, plates formed with horizontally-extending slots, and plates adapted to swing on said pivot-plates and formed with slots adapted to register with the slots of the pivot-plates when said swinging plates are swung to horizontal position, of a sash, and 70 pins upon which said sash is adapted to slide, resting in the slots of said pivot-plates and adapted to move in the slots of said swinging plates when the latter are in horizontal position, substantially as described.

75 8. The combination with a window-frame, downwardly-swinging slotted plates carried thereby, and gravity-catches for holding said plates raised, of a sash, and pins adapted to move in said slots and connected with said sash, substantially as described.

9. The combination with a window-frame, and slotted swiveled plates carried thereby, of a sash having grooved side rails formed with retaining-walls, and pins engaging in 85 the grooves of the sash and slots of the plates and having their respective ends headed, substantially as described.

In testimony whereof we affix our signatures in presence of two witnesses.

FRED B. SMALL.
JAMES C. MULLIGAN.
